P. McGUIRE.

TIE SPACER,

APPLICATION FILED OCT. 10, 1919.

1,346,225.

Patented July 13, 1920.

By *Geo. P. Kimmel*
Attorney

UNITED STATES PATENT OFFICE.

PHILLIP McGUIRE, OF STAPLES, MINNESOTA.

TIE-SPACER.

1,346,225.

Specification of Letters Patent. Patented July 13, 1920.

Application filed October 10, 1919. Serial No. 329,749.

To all whom it may concern:

Be it known that I, PHILLIP McGUIRE, a citizen of the United States, residing at Staples, in the county of Todd and State of Minnesota, have invented certain new and useful Improvements in Tie-Spacers, of which the following is a specification.

This invention relates to improvements in tools to be utilized in shifting and securing uniform spacing between the ties of railway tracks.

The invention has for its object to provide a tool of this character embodying such features of construction as permit the ties to be moved by a step by step process so as not to sacrifice the leverage exerted by the fulcrum bar as the tie is advanced to the desired position.

Another object is the provision of a tie spacer including a two part tie engaging element constituting a fulcrum for the hand lever bar, which may be folded in compact form for convenience in transportation.

With these and other objects in view as will appear as the description proceeds, the invention comprises the novel features of construction, combination and arrangement of parts which will be more fully described in the following specification and set forth with particularity in the claims appended hereto.

Figure 1 represents a perspective view of the invention applied to use.

Fig. 2 represents a fragmentary longitudinal sectional view therethrough.

Referring to the drawing in detail, wherein similar reference numerals designate corresponding parts throughout the several views, the numerals 5 and 6 indicate the separable and foldable parts of the track engaging element constituting a means for adjustably supporting the fulcrum bar 7.

The part 5 of the tie engaging element consists of a pair of parallel spaced bars 8 provided at one terminal with bevels providing the anchoring points 9 for engagement in one of the sides of a tie adjacent the one to be moved or properly spaced. The side members of the bars 8 are rigidly maintained in parallel relation by the spacing rivets 12, while the lower edges of the side members adjacent their inner terminals are adapted to engage the top of a fixed tie to assist in

maintaining the tie engaging element in position. 55

The other part 6 of the tie engaging element is in the form of an elongated loop the relatively long parallel portions of which are maintained in spaced relation by the rigid rivets or bolts 12. 60

A bolt 13 is fitted in registered apertures formed in the adjacent terminals of the tie engaging members 5 and 6 and a nut 14 is threaded upon the extremity of the bolt whereby the latter is prevented from accidental displacement. 65

A bolt 15 is positioned through apertures formed in the terminal portions of the side members of the part 5 and is slidably received in accurate slots 16 formed in the terminal portions of the loop part 6. The slots 16 are arranged concentric with the pivot bolt 13 and owing to their utilization, it is possible to fold the parts 5 and 6 together in one direction. Relative movement 75 of the sections in the opposite direction, however, is limited due to engagement of the bolt 15 with the terminals of the slots 16. 70

In use, the part 5 of the tie engaging element is placed upon a tie A which has already been set and secured adjacent to the tie B to be spaced, the part 6 extending across and resting upon the tie B and the pointed terminals 9 of the part 5 are engaged with an adjacent tie A. The pointed 85 extremity of the lever bar 7 is subsequently inserted between two of the fulcrum rivets 12 and the bar is swung so as to cause the tie B to move in the proper direction. The movement of the tie B is continued by repeated oscillations of the hand lever 7 upon successive fulcrum rivets 12 until the tie has been advanced to the proper position with relation to the set tie A, which distance may be readily determined by reference to 95 the uniformly spaced rivets 12 of the part 6. 90

What I claim is:

1. A tie spacer comprising a pair of engaging members movable into angular relation whereby one of said members may be 100 engaged with a tie, and a plurality of fulcrum members carried by one of the tie engaging members.

2. A tie spacer comprising a pair of pivotally connected and foldable tie engaging 105 parts, means limiting the swinging move-

ment of the parts in one direction, and a plurality of fulcrum members carried by one of the parts, adapted to engage a fulcrum bar.

5 3. A tie spacer comprising a pair of spaced side members, fulcrum members connecting the side members adapted to engage a ful-

crum bar, and a foldable tie engaging anchoring member carried by the side members.

In testimony whereof I affix my signature hereto.

PHILLIP McGUIRE.
